[57] CLAIM

The ornamental design for a suture washer, as shown and described.

DESCRIPTION

FIG. 1 is a top perspective view of a suture washer showing my new design, the broken lines are for illustrative purpose only and form no part of the claimed design;

FIG. 2 is a side view of the suture washer, the opposite side being a mirror image thereof;

FIG. 3 is a left view thereof;

FIG. 4 is a bottom view thereof;

FIG. 5 is a right view thereof; and,

FIG. 6 is a top view thereof.
